FIG. 5

INVENTOR
ARTHUR E. SWEET,
BY

Edward B. Birkhead,
ATTORNEY

UNITED STATES PATENT OFFICE.

ARTHUR E. SWEET, OF PORTLAND, OREGON, ASSIGNOR TO GEORGE PENKETH AND
GEORGE RODGERS, BOTH OF PORTLAND, OREGON.

OIL-BURNER.

1,319,020.

Specification of Letters Patent.

Patented Oct. 14, 1919.

Application filed April 26, 1918. Serial No. 292,898.

To all whom it may concern:

Be it known that I, ARTHUR E. SWEET, a citizen of the United States, and a resident of the city of Portland, in the county of Multnomah and State of Oregon, have invented a certain new and useful Oil-Burner, of which the following is a specification.

My invention relates more particularly to that class of devices which permit the burning of a liquid fuel in the ordinary cook stove, heater or furnace.

The object of my invention is to provide an exceedingly simple, safe, noiseless, efficient and convenient means for converting kerosene and cheaper oils into a properly mixed gas for heating and cooking purposes.

It being a well known fact that existing devices for the above mentioned purposes are noisy, dangerous and more or less difficult to operate, which objections I have overcome in the manner illustrated in accompanying drawing and explained in the specification following.

Referring to the drawing, Figure 1 is a front elevation of my device of which Fig. 2 is a sectional elevation along the line 2—2 in Fig. 3. Fig. 3 is a plan; Fig. 4 is a detail in plan showing the burner cap moved to one side and exposing the gas outlet. Fig. 5 is a partial bottom view showing the means for regulating the mixture.

Similar letters and numbers of reference refer to the same or similar parts throughout the several views.

On the flat base A¹ are formed the walls A² which form the lighting cup A³, in the floor of which is located the oil inlet hole A⁴. On the base A¹ are also positioned the lugs A⁵ which serve to support the piping. A⁶ is a clamp which holds the piping against the lugs A⁵, said clamp being held in place by the screws A⁷. A⁸ is a baffle plate which is suspended from the overhead piping by the hook A⁹. A¹⁰ is asbestos packing whose function it is to exclude all air from the combustion which does not pass through the mixer.

F¹ is a generating pipe which is closed at one end by the plug F² which may be removed for cleansing purposes. The end F³ of the generating pipe F¹ is joined to an oil supply pipe. F⁴ is a gas outlet hole which is formed in the generating pipe F¹. F⁵ are coils formed in the generating pipe

ing to expose a greater area to the action of the heat. Over the gas outlet hole F⁴ is placed the gas and air mixing chamber F⁶, underneath which and extending through the base A¹ are the holes F⁷ which admit air to the jet of gas escaping from the hole F⁴ and which holes may be closed as desired by the cover F⁸ which rotates on the pivot F⁹ and is operated by the handle F¹⁰. It being understood that the cover F⁸ is supplied with the holes F¹¹ which correspond with the holes F⁷ so that the openings F⁷ may be entirely uncovered if desired. F¹² is a depression in the base A¹ for receiving the gas and air mixing chamber F⁶. Said cap is cut away at F¹³ for the pipe F¹.

H¹ is a pressure oil tank on which is the gage H². H³ is an oil supply pipe leading from the tank H¹ to the T fitting H⁴. H⁵ is an oil line of small pipe leading from the T H⁴ to the inlet hole A⁴ in the lighting cup A³. The flow of oil for generating purposes is regulated by the needle valve H⁶ in the pipe H⁵. This valve is of course used only for starting purposes. From the T H⁴ extends the oil supply pipe H⁷ which is joined to the pipe end F⁸, which pipe H⁷ is supplied with the needle valve H⁸ which regulates the flow of oil to the generator pipe F¹.

By means of the construction thus described, I entirely eliminate backfiring, noise, danger from explosion and the usual inconvenience of starting. I am also able to secure a great range of temperature as well as to insure a uniform application of heat to the stove oven.

The stove walls are indicated at K¹ while the stove grate is indicated as K².

While I have thus illustrated and described my invention it is not my intention to limit myself to this precise form or method of application of my invention but intend that it shall cover all forms and modifications that fall fairly within the appended claim.

What I claim as new and desire to protect by Letters Patent of the United States is:

In an oil burner, the combination of a base plate adapted to rest on the grate of a stove in a manner to exclude all of the air from passing around the base plate, a lighting cup formed on said base plate, a generating means consisting of a coil of pipe secured above said base plate, said pipe having a gas

outlet hole located on its upper side near the center of the base plate, a gas and air mixing chamber consisting of a hollow frustum of a cone which is notched to straddle said generator pipe over said gas outlet hole and adapted to set in a recess in the base plate, a baffle suspended from a coil of said generator pipe directly over the gas and air mixing chamber, an air admission means consisting of radial openings in said base plate

under said gas and air mixing chamber and a rotatable cover plate adapted to vary the size of said openings manually, a means for delivering oil under pressure to said lighting cup and generating pipe, and a means for excluding all air from the combustion chamber and absorbing any surplus of oil consisting of an asbestos packing.

ARTHUR E. SWEET.
